UNITED STATES PATENT OFFICE.

DANIEL WEBSTER ROHRER, OF TRENTON, NEW JERSEY.

PERMUTATION PADLOCK.

Application filed December 6, 1921. Serial No. 520,321.

To all whom it may concern:

Be it known that I, DANIEL WEBSTER ROHRER, a citizen of the United States, and a resident of Trenton, in the county of Mercer and State of New Jersey, have invented a new and Improved Permutation Padlock, of which the following is a full, clear, and exact description:

The present invention relates to new and useful improvements in padlocks, and more particularly pertains to padlocks known as permutation padlocks.

It is one of the primary objects of the invention to provide a permutation padlock in which the use of a multiplicity of tumblers is dispensed with.

It is a further object of the invention to so construct a padlock that the locking means is positively actuated to release the shackle 20 of the padlock.

It is a still further object of the invention to provide a new and improved permutation means for changing the combination of locks of this character.

With the above and other objects in view, reference is had to the accompanying drawings, in which

Figure 1 is a view in elevation of a lock constructed in accordance with the present invention;

Fig. 2 is a vertical sectional view thereof;

Fig. 3 is a vertical sectional view taken at right angles to Fig. 2 and on the line 3—3 thereof;

Fig. 4 is a vertical sectional view showing the several parts in the position they assume when the lock is set and in position to permit of the opening thereof;

Fig. 5 is a similar view showing the position of the parts when the locking mechanism is released, the shackle being shown in released position in dotted lines;

Fig. 6 is a horizontal sectional view taken on the line 6—6 of Fig. 2, and

Fig. 7 is a detail enlarged plan view of a portion of the actuating means of the lock.

Referring more particularly to the drawings, the reference character 10 designates the lock housing, and said lock housing is provided with a recess 11 preferably circular in form. Mounted within the lock housing in the ordinary manner is a shackle 12, and said shackle 12 is adapted to be forced outwardly to the dotted line position shown in Fig. 5, by means of a spring 13 surrounding a guide rod 14, and having its upper end en-

gaged with the free edge of one of the legs of said shackle 12, as more clearly shown in said figure. One of the legs of the shackle 12 is provided with a notched portion 15, and adapted to engage the notched portion 15 to retain the shackle in its closed position, is a sliding bolt or similar member 16. This sliding bolt 16 is mounted in a recess 17 in the upper portion of the lock and between the openings in which the shackle operates.

Mounted within the recess 11 of the lock housing 10, is a pivoted lever 18, said lever being pivotally mounted by means of a screw 19 or the like, and surrounding said screw is a spring 20, one end of which is received in the lock housing 10, as indicated by the reference character 21, the other end being attached to the pivoted lever 18, as at 22, which construction is clearly shown in Fig. 75. One end of the lever 18 is received in a cut-out portion 23 in the sliding bolt 16, and the other end of said lever is provided with a rigid pin 24, the purpose of which will be hereinafter more fully described.

The reference character 25 designates a rectangular plate adapted to be rotatably mounted in the front wall of the housing 10, and said plate has an extension 26, by means of which it is mounted. Projecting from the extension 26, is a square extension 27, and mounted on said square extension 27 is a dial plate 28. This dial plate 28 is retained in position by means of a spring washer 29, and a nut 30, which latter engages the reduced screw-threaded end 31 of the extension 27. By this construction it is apparent that as the dial plate 28 is turned, the plate 25 on the interior of the lock housing will be likewise rotated.

Carried by the plate 25 and pivotally secured thereto, as at 32, is a pawl or dog 33, and said pawl or dog 33 is provided with a cut-out portion 34, which forms a passage-way therethrough. This dog or pawl 33 is so positioned with respect to the plate 25, that as the plate is rotated, the dog or pawl 33 passes into the path of the stationary pin 24 on the pivoted lever 18. One end of the passage formed by the cut-out portion 34 is closed by means of a pivoted pawl 35 mounted as at 36 and normally maintained in position to close the passage formed by the cut-out portion 34 by means of a spring 37. This dog or pawl 33 is provided with a plurality of notches 38, and slightly offset with respect to the end of the

pawl or dog 33, is a notch 39. The pawl or dog 33 as more clearly shown in Figs. 4 and 5, is maintained under normal conditions in alignment with the rectangular plate 25 upon which it is mounted, by means of springs 40 or the like, secured to the under side of the pawl or dog, and to the pin upon which it is pivotally mounted, in such a manner that as the plate is rotated within 10 the recess 11 of the housing 10, the pin when engaged by the pawl will move around the end thereof owing to the resiliency of the spring controlling said pawl.

The device operates in the following manner:

When the dial plate 28 is turned to the right in Fig. 1, the pawl will engage the pin 24 and said pin will be successively engaged with the notches 38 and the notch 39 20 and will pass around to the opposite side of the pawl without actuating the rocking lever 18. When the dial plate is rotated to the left in said figure, the pin passes through the passage formed by the cut-out 25 portion 34 and engages the pawl 35, which permits of its passing entirely through the passage formed by the cut-out portion 34 without actuating the pivoted lever 18.

To open the lock, a definite combination 30 must be known, and said combination is determined by the relative position of the dial plate 28 and the rectangular plate 25 upon which the pawl or dog 33 is carried within the lock housing. Assuming the 35 combination be as follows: "30" and "35". The dial plate is moved to the right until the numeral "30" thereon is opposite the indicating member 50 on the lock housing 10. After this has been done, the parts will be 40 positioned as shown in Fig. 4, in the following manner: The pawl or dog 33 has moved into engagement with the pin 24 and the notches 38 have successfully engaged with the pin and the latter is finally positioned in the notch 39 as shown. With 45 the parts so positioned, the dial plate is then moved to the left four notches, as shown by the arrow in Fig. 5, which action rocks the pivoted lever 18 about its pivotal point 50 and slides the bolt 16 out of engagement with the notched portion 15 of the shackle 12 and permits the shackle to move to the dotted line position shown in Fig. 5, under the influence of the spring 13. The lock is 55 then opened.

When it is desired to change the combina-

tion, the nut 30 is removed after which the dial plate is free to be removed and shifted relative to the squared extension 27 of the rectangular plate 25, after which it is obvious that a new set of figures will have to be employed to properly position the parts to open the lock.

From the foregoing it is apparent that the present invention provides a new and improved form of permutation lock in which the use of a multiplicity of tumblers is dispensed with, and, at the same time, a lock which is both simple in construction and easy of operation is obtained.

I claim:

1. In a lock, a lock housing, a shackle, means for engaging the shackle to retain the shackle within the lock housing, means for operating said shackle-retaining means, and means for operating the shackle-retaining means operating means to release the shackle, said last-mentioned means comprising a rotating member and a spring-pressed pawl carried thereby.

2. In a lock, a housing, a shackle carried thereby, means for retaining said shackle in position in the housing, said means comprising a sliding bolt, a pivoted lever for operating said sliding bolt, a rotatable member mounted within the housing, and a pivoted resilient pawl adapted to operate said pivoted lever to release the shackle-retaining means.

3. In a lock, a housing, a shackle carried by the housing, a sliding bolt for engagement with the shackle to retain the same within the housing, a pivoted lever for actuating said sliding bolt to release the shackle, a spring-pressed pawl for operating said pivoted lever, and a rotating member carrying said spring-pressed pawl.

4. In a lock, a housing, a shackle carried by the housing, a sliding bolt carried by the housing and adapted for engagement with the shackle to retain the shackle within the housing, a pivoted lever carried by the housing and adapted for engagement with said sliding bolt to move the same to position where it will release the shackle, a rotating member mounted within the housing, and means carried by said rotating member and adapted for engagement with the pivoted lever to operate the latter to move the sliding bolt and release the shackle, substantially as described.

DANIEL WEBSTER ROHRER.
